CLAIM

The ornamental design for a multi-chamber heat sink module, as shown and described.

DESCRIPTION

FIG. 1 is top, front perspective view of a multi-chamber heat sink module;

FIG. 2 is a bottom, front perspective view of the multi-chamber heat sink module of FIG. 1;

FIG. 3 is a top, rear perspective view of the multi-chamber heat sink module of FIG. 1;

FIG. 4 is a bottom, rear perspective view of the multi-chamber heat sink module of FIG. 1;

FIG. 5 is a top view of the multi-chamber heat sink module of FIG. 1;

FIG. 6 is a bottom view of the multi-chamber heat sink module of FIG. 1;

FIG. 7 is a front view of the multi-chamber heat sink module of FIG. 1;

FIG. 8 is a rear view of the multi-chamber heat sink module of FIG. 1;

FIG. 9 is a left side view of the multi-chamber heat sink module of FIG. 1; and,

FIG. 10 is a right side view of the multi-chamber heat sink module of FIG. 1.

The broken lines illustrate portions of the multi-chamber heat sink module and form no part of the claimed design.

1 Claim, 5 Drawing Sheets
